FIG. 11

FIG. 12

FIG. 13

FIG. 14

FIG. 15

FIG. 16

FIG. 17

FIGURE 1 is a front elevation of the king in a set of chessmen, showing my new design;

FIGURE 2 is the side elevation of the king;

FIGURE 3 is a rear elevation of the king;

FIGURE 4 is a top plan view of FIGURE 1;

FIGURE 5 is a front elevational view of the queen, which is the same from all sides;

FIGURE 6 is the top plan view of FIGURE 5;

FIGURE 7 is the side elevational view of the knight;

FIGURE 8 is the front elevational view of the knight;

FIGURE 9 is the rear elevational view of the knight;

FIGURE 10 is the top plan view of FIGURE 7;

FIGURE 11 is the side elevational view of the bishop;

FIGURE 12 is the front elevational view of the bishop, which is identical to the rear view thereof;

FIGURE 13 is the top plan view of FIGURE 12;

FIGURE 14 is the elevational view of the castle or rook, which is the same from all sides;

FIGURE 15 is the top plan view of FIGURE 14;

FIGURE 16 is the elevational view of the pawn, which is the same from all sides, and

FIGURE 17 is the top plan view of FIGURE 16.

I claim:

The ornamental design for a set of chessmen, as shown and described.
